CONTAINER

Harold L. Myers, Morristown, N. J.

Application June 3, 1936, Serial No. 83,183

6 Claims. (Cl. 206—44)

The invention relates to containers for articles of merchandise and has for its object to provide a container constructed in a novel manner to constitute an efficient holder or package in which the articles of merchandise may be sold, stored and shipped and which further is arranged to serve as a display device whereby said articles may be attractively displayed for sale. The invention contemplates further the provision of a container which in its initial condition is of flat shape for easy storage and shipment and is adapted to be folded or adjusted to an operative condition in a simple and easy manner without the necessity for any complicated mechanism or any particular skill on the part of the operator. Other more specific objects will appear from the description hereinafter and the features of novelty will be pointed out in the claims.

In the accompanying drawings, which show an example of the invention without defining its limits, Fig. 1 is a perspective view of the container in the form of a package; Fig. 2 is a sectional view on the line 2—2 of Fig. 1; Fig. 3 is a perspective view of the container adjusted to the form of a display device; Fig. 4 is a sectional view on the line 4—4 of Fig. 3; Fig. 5 is a fragmentary section on the line 5—5 of Fig. 4; Fig. 6 is a fragmentary perspective of the container in a partly set up condition; Figs. 7 and 8 are face views of the blanks from which the novel container is constructed, and Fig. 9 is a face view showing the two blanks of Figs. 7 and 8 combined with each other and illustrating the container in its flat shape prior to being folded or set up for use.

In its illustrated form the novel container before being assembled and folded into its final shape comprises the main blank A shown in Fig. 7 and the auxiliary blank B shown in Fig. 8. The main blank A consists of a major section or outside rear panel 10 foldably connected along a score line 11 with an outside bottom panel 12 which in turn is foldably connected along a score line 13 with an outside front panel 14. The latter in turn is foldably connected along a score line 15 with an inside front panel 16 which itself is foldably connected along a score line 17 with an inside bottom panel 18. An auxiliary section or inside rear panel 19 is foldably connected with the inside bottom panel 18 along a score line 20; as illustrated in Fig. 7 the inside rear panel 19 preferably is slightly less in transverse width than the major section or outside rear panel 10 and is of approximately the same longitudinal

dimension as said panel 10 for the purpose to be more fully set forth hereinafter.

At its opposite longitudinal edges the outside rear panel 10 is foldably connected with side members 21 along score lines 22 which, in the illustrated example, extend from the free edge of the panel 10 to the score line 11; as shown in Fig. 1 the side members 21 are preferably provided with inclined outer edges 23 although this shaping of said side members 21 is not arbitrarily necessary and may be changed if desired. Bottom flaps 24 are foldably connected with the side members 21 along score lines 25 which may comprise extensions of the previously mentioned score line 11 as illustrated in Fig. 1; in addition locking tabs 26 project outwardly from the side members 21 and are foldably connected therewith along score lines 27 which extend from the lower ends of the side edges 23 to the score lines 25.

As shown in Fig. 7 the panels 10, 12, 14, 16 and 18 are located in sequence in conterminous relation to each other with the inside rear panel 19 projecting from the panel 18 in centralized relation thereto.

The auxiliary blank B illustrated in Fig. 8 consists of a main section 28 foldably connected along a score line 29 with an intermediate section 30 which in turn is connected along a score line 31 with an end section 32; the sections 28, 30 and 32 as shown in Fig. 8 are of the same transverse dimensions and are located in conterminous relation to each other, and preferably are all of a width corresponding approximately to the width of the inside rear panel 19. The auxiliary blank of Fig. 8 is further provided with a predetermined number of slots 33 extending lengthwise of said auxiliary blank and of predetermined length for the purpose to be more fully described later on; in the illustrated example the slots 33 are partly formed in the panel 32 and partly in the panel 30 or in other words extend across the score line 31. The shape and transverse dimensions of the slots 33 is dependent upon the type of fastening means used in the device as will appear more fully hereinafter and in the illustrated example said slots 33 are accordingly of rectangular form. The number of slots 33 included in the auxiliary blank is dependent upon its size and upon the dimensions of the container for which it is designed; in some cases the auxiliary blank may therefore be provided with more than two slots 33 while in another case one slot 33 will be sufficient.

In order to operatively combine the main blank 55

A of Fig. 7 and the auxiliary blank B of Fig. 8 in the form of the unit shown in Fig. 9, the inside front panel 16 is folded on the score line 15 into surface engagement with the outside front panel 14 to thereby bring the inside bottom panel 18 and the inside rear panel 19 into corresponding surface engagement with the outside bottom panel 12 and the outside rear panel 10 respectively; in this condition the score line 17 registers with the score line 13 while the score line 20 is in registry with the score line 11 for the purpose to be more fully set forth hereinafter. The auxiliary blank B is now inserted between the panels 10 and 19 in registry therewith after which fastening devices such as wire staples 34 are driven through the panels 19 and 10 to secure these panels in operative relation to each other and so as to pass through the slots 33 of the auxiliary blank B as illustrated in Fig. 9. At this stage the auxiliary blank B accordingly is slidably mounted between the panels 19 and 10 and is restricted in its sliding movements by the slots 33 in co-operation with the fastening devices 34.

It will be noted that the unit shown in Fig. 9 consisting of the combined blanks A and B is absolutely flat and accordingly is capable of being efficiently stored in relatively large quantities in limited spaces and likewise is adapted to be easily shipped in corresponding large quantities in packages of minimum dimensions.

To set up the unit shown in Fig. 9 in the form of the container illustrated in Figs. 1-4 inclusive, the two bottom panels 12 and 18 are folded on the registering score lines 11 and 17 into perpendicular horizontal relation to the rear panels 19 and 10 after which the front panels 14 and 16 are folded on the registering score lines 13 and 17 into upright relation to the bottom panels 12 and 18, or in other words, in spaced parallel relation to the rear panels 19 and 10. To facilitate the further folding of the unit of Fig. 9 the bottom flaps 24 are first preferably folded on the score lines 25 into surface engagement with the side members 21 after which the latter are folded upon the score lines 22 into perpendicular relation to the panel 10 and secured in this position by bending the locking tabs 26 upon the score lines 27 and inserting said tabs 26 into the space between the front panels 14 and 16; the fact that the inside rear panel 19 is of slightly less width than the outside rear panel 10 enables the side members 21 to be folded as described without interference, it being understood that the correspondingly lesser width of the auxiliary blank B also facilitates such folding of said side members 21. After the latter have been adjusted and locked in place as described, the bottom flaps 24 are folded downwardly upon the score lines 25 into surface engagement with the inside bottom panel 18 so as to project toward each other as illustrated in Fig. 5. At this stage the container has the appearance illustrated in Fig. 3 in which the auxiliary blank B projects upwardly beyond the rear panels 10 and 19 and the side members 21 are locked in connection with the front panels 14 and 16 to rigidly fix the main blank A in the form of a container. The articles of merchandise for which the latter is designed may now be inserted into said container to the capacity thereof after which the auxiliary blank B is pulled upwardly until the score line 31 registers with the upper edge of the inside rear panel 19. The intermediate section 30 of the blank B is then folded on the

score line 31 to the horizontal position shown in Fig. 1 after which the main section 28 is folded downwardly on the score line 29 and inserted between the inside front panel 16 and the articles of merchandise located in the container. At this stage the latter appears as illustrated in Fig. 1 in which it will be noted that the auxiliary blank B constitutes a cover to enclose the contents of the container and to form a completely closed package of merchandise adapted to be efficiently stored and shipped.

When it is desired to display the articles of merchandise in the container for sale or other disposal, the container may be adjusted to the display position illustrated in Fig. 3 by withdrawing the main section 28 from its position between the inside front panel 16 and the merchandise in the container and then folding the main and intermediate sections 28 and 30 to an upright position. The auxiliary blank B in this condition is then slidably moved downwardly between the inside rear panel 19 and the outside rear panel 10 to a position in which both score lines 29 and 31 are located below the upper edge of the outside rear panel 10 with the score line 29 in proximity to the upper edges of said rear panels 19 and 10 as illustrated in Fig. 3. The main section 28 is thereby fixed in the upright vertical position shown in Fig. 3 so as to project upwardly beyond the rear panels 10 and 19 and so as to completely expose the contents of the container and to permit the articles of merchandise to be removed therefrom at will for purposes of sale or other disposal. The sliding movements of the auxiliary blank B are limited by the fastening devices 34 in co-operation with the slots 33 and said auxiliary blank B is guided in such vertical movements by the side members 21 and the rear panels 19 and 10 as will be apparent. By providing the inside surface of the main section 28 with suitable advertising matter, this main section when occupying the vertical upright position shown in Fig. 3 may constitute an attractive advertising or display card setting forth information regarding the articles of merchandise located in the container.

The auxiliary blank B accordingly performs a double function or in other words is arranged to serve as a cover or closure for the container to form a closed package and as an advertising device in the display position of the container. The latter in its entirety is of simple construction and is capable of being readily folded and set up in the form of an efficient container without requiring any complicated mechanism or any particular skill on the part of the operator to effect this result. The novel device may be constructed in any dimensions and in many different shapes dependent upon the articles of merchandise to be accommodated in the container and in all of its forms provides not only an efficient package for storage and shipment purposes but also provides a display device whereby said articles of merchandise may be displayed for sale or other disposition in an attractive manner.

Various changes in the specific forms shown and described may be made within the scope of the claims without departing from the spirit of the invention.

I claim:

1. A device of the kind described comprising a plurality of panels foldable relatively to each other to form a container including outer and inner rear panels lying in surface relation to each other, an independent member provided with

- spaced parallel slots and consisting of foldably connected sections slidably mounted between said outer and inner rear panels, said independent member being outwardly slidable relatively to said container and foldable to constitute a cover therefor and being slidably adjustable to an upright position to constitute a display card, and fastening devices for fastening said outer and inner rear panels together in surface relation and 10 extending through said slots for arresting the outwardly sliding movements of said independent member.
2. A device of the kind described comprising a container consisting of inner and outer front panels foldably connected with and lying in surface relation to each other, bottom panels foldably connected with each of said front panels respectively and lying in surface engagement with each other, inner and outer rear panels foldably connected with each of said bottom panels respectively and lying in surface relation to each other, side members foldably connected with said outer rear panel and projecting toward said front panels, locking tabs foldably connected with said side members and extending between said front panels, bottom flaps foldably connected with said side members and lying in surface engagement with one of said bottom panels, means for fastening said rear panels in said surface relation, an independent member slidably mounted between said rear panels and adjustable relatively to said container to constitute a cover therefor and to an upright position relatively to said container to constitute a display card, and means 30 on said independent member co-operating with said fastening means to limit the sliding movements of said independent member.
3. A device of the kind described comprising connected panels foldable relatively to each other to form a container in which two upright panels lie in surface relation to each other, an independent member slidably mounted between said two upright panels in opposite surface relation thereto and entirely between opposite side edges of said upright panels, said independent member being adjustable outwardly and inwardly relatively to said upright panels and consisting of connected sections foldable relatively to each other when said member is adjusted outwardly, to form a cover for said container and held against relative folding when said member is adjusted inwardly whereby one section thereof projects beyond said container in upright relation thereto, fastening means independent of any foldable connection between said two upright panels for fixing the latter in said surface relation, and means on said independent member co-operating with said fastening means for arresting the outward adjustment of said independent member.
4. A device of the kind described comprising connected panels foldable relatively to each other to form a container in which two upright panels lie in surface relation to each other, an independent member slidably mounted between said two upright panels and adjustable outwardly and
- inwardly relatively thereto, said independent member being provided with at least one slot extending lengthwise thereof, and consisting of connected sections foldable relatively to each other when said member is adjusted outwardly, to form a cover for said container and held against relative folding when said member is adjusted inwardly whereby one section thereof projects beyond said container in upright relation thereto, and fastening means extending transversely through the slot of said independent member for securing said two upright panels in said surface relation and co-operating with said slot to arrest the outward adjustment of said independent member.
5. A device of the kind described comprising a container consisting of foldably connected panels and including two bottom panels and inner and outer rear panels foldably connected with each of said bottom panels respectively and projecting upwardly therefrom in surface relation to each other, an independent member slidably mounted between said inner and outer rear panels and adjustable outwardly and inwardly relatively thereto, said independent member being provided with at least one lengthwise extending slot and consisting of connected sections foldable relatively to each other when said member is adjusted outwardly, to form a cover for said container and held against relative folding when said member is adjusted inwardly whereby one section of said independent member projects upwardly beyond said rear panels and is supported thereby to constitute an upright display card, and a fastening device extending transversely through the slot of said independent member for securing said inner and outer rear panels in said surface relation to each other and co-operating with said slot to arrest the outward adjustment of said independent member.
6. A device of the kind described comprising a container including two upright panels in surface relation to each other, an independent member slidably mounted between said two upright panels in opposite surface relation thereto and entirely between opposite side edges of said upright panels, said independent member being adjustable outwardly and inwardly relatively to said upright panels and consisting of connected sections foldable relatively to each other when said member is adjusted outwardly, to form a cover for said container and held against relative folding when said member is adjusted inwardly whereby one section thereof projects beyond said container in upright relation thereto, fastening means extending between said two upright panels and transversely across the sliding path of said independent member for securing said two upright panels in said surface relation, and means on said independent member co-operating with said fastening means without interference with the sliding movements of said independent member to permit a predetermined limited outward adjustment of said member.
